UNITED STATES PATENT OFFICE

147,510

DESIGN FOR AN EARRING

Carl Schraysshuen, Providence, R. I.

Application February 20, 1946, Serial No. 126,772

Term of patent 7 years

(Cl. D45—9)

To all whom it may concern:

Be it known that I, Carl Schraysshuen, a citizen of the United States, residing at Providence, in the county of Providence and State of Rhode Island, have invented a new, original, and ornamental Design for an Earring, of which the following is a specification, reference being had to the accompanying drawing, constituting a part thereof.

Fig. 1 is a front elevational view of an earring, showing my new design; and

Fig. 2 is a side view thereof.

I claim:

The ornamental design for an earring, substantially as shown.

CARL SCHRAYSSHUEN.
